(57) **CLAIM**

The ornamental design for a concentrate jar, as shown and described.

DESCRIPTION

FIG. 1 is a front perspective view of a concentrate jar, showing my new design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof;

FIG. 7 is a bottom plan view thereof; and,

FIG. 8 is a front perspective view thereof, with a lid covering a top portion of the concentrate jar.

The broken lines shown in the drawings in FIGS. 1–7 depict portions of the concentrate jar that form no part of the claimed design. The broken lines shown in the drawings in FIG. 8 depict environmental structure that forms no part of the claimed design.

1 Claim, 5 Drawing Sheets
